(57) **CLAIM**

The ornamental design for a self-standing produce pouch, as shown and described.

DESCRIPTION

FIG. 1 is a perspective view of a self-standing produce pouch showing our new design;

FIG. 2 is front view thereof;

FIG. 3 is a right side view, the left side view being a mirror image thereof;

FIG. 4 is a top view thereof;

FIG. 5 is a bottom view thereof;

FIG. 6 is an alternate front elevation view thereof; and,

FIG. 7 is a perspective view of the self-standing produce pouch with a slider closure.

The broken line showing a tear-away flap in FIG. 6 is included for the purpose of illustrating environmental structure and forms no part of the claimed design.

1 Claim, 6 Drawing Sheets
